UNITED STATES PATENT OFFICE.

FREDERICK GIRTANNER, OF NEW YORK, N. Y., ASSIGNOR TO THE UNITED STATES MINING & TRADING COMPANY, A CORPORATION OF NEW YORK.

FURNACE-GRAVE FOR SMOKELESS COMBUSTION.

SPECIFICATION forming part of Letters Patent No. 760,444, dated May 24, 1904.

Application filed December 1, 1902. Serial No. 133,401. (No model.)

To all whom it may concern:

Be it known that I, FREDERICK GIRTANNER, a citizen of the United States of America, residing at the city of New York, in the county 5 of New York and State of New York, have invented certain new and useful Improvements in Furnace-Grates for Smokeless Combustion, of which the following is a specification.

My invention has reference to improvements in grates especially adapted for boiler-furnaces, and has for its object essentially the combustion of bituminous or soft coal of the lowest grade without smoke and at the same time obtaining the highest possible efficiency.

To this end my invention consists, essentially, in a traveling distilling-grate having the individual grate-bars overlapping, so as to exclude ingress of air from below, an inclined combustion-grate adapted to receive 20 the coked matter from the traveling distilling-grate, and a dumping-grate adapted to discharge the ashes.

My invention also consists in certain other novel features of construction, as will herein-after be fully pointed out in connection with the annexed sheets of drawings, in which—

Figure 1 represents a vertical section of a grate embodying my invention. Fig. 2 is a side elevation of the same. Fig. 3 is a front 30 view of Figs. 1 and 2. Fig. 4 is an enlarged perspective of a portion of the traveling distilling-grate. Fig. 5 is a perspective view of a clearing-roll interposed between the traveling distilling-grate and the inclined combustion-grate. Fig. 6 is a side elevation of the hopper and its operating means for automatic stokers. Fig. 7 is a longitudinal section showing the grate applied to an internally-fired boiler. Fig. 8 is a sectional end elevation of 40 Fig. 7. Fig. 9 is a vertical section on the line 8 8, Fig. 7.

Similar letters and numerals of reference designate corresponding parts throughout the several views of the drawings.

Referring now to the drawings, the letter A designates side frames adapted to be set into or between the furnace-walls of a boiler, the same preferably being kept at a slight dis-

tance from the side walls, so as to permit easy removal for repairs. Upon the side frames 50 are supported and arranged, first, a traveling distilling-grate B, secondly, a combustion-grate C, and, thirdly, a dumping-grate D, arranged in order from the exterior of the furnace. The traveling grate consists of a series 55 of grate-bars b, arranged to overlap each other, as shown in Fig. 1, and carried by conveying-chains 1, passing over suitable chain-wheels 2 2, arranged on opposite interior sides of the frame and mounted on parallel shafts 3 3. 60 Motion is imparted to the outer shaft 3 by means of a small engine E, having its piston-rod e connected with a worm-shaft 4, engaging a worm-wheel 5, rigidly secured to the outer shaft 3, thus imparting a slow movement 65 to the worm-wheel 5 for gradually advancing the upper portion of the traveling distilling-grate B toward the combustion-grate C. The particular mechanism for producing a slow movement of the traveling distilling-grate B, 70 either intermittent or continuous, forms no part of my present invention, as any well-known mechanism for this purpose may be employed. The traveling distilling-grate has its grate-bars substantially in contact with each 75 other at the overlapping portions, so as to permit practically little or no ingress of air from below to the mass of fuel thereon, air being admitted only from above through the opening or openings 7, through which the supply of fuel is 80 introduced from the hopper F, into which the fuel is shoveled as usual in stoking apparatus, or supplied by a distributer.

In practice I provide the links 8 of the chains 1 with dovetail grooves 9 and the grate-bars b with longitudinal dovetails 10, adapted to fit the dovetail grooves 9, so that the individual bars can readily be inserted or removed, while at the same time they are securely held to the chain while traveling.

The combustion-grate C is spaced from the distilling-grate B, and between the same is arranged a clearing-roll I, provided with a corrugated or toothed surface, said roll being loosely mounted upon a shaft and divided in 95 the direction of its length into several sections

i, each independent of the other. This roll has for its function to guide the coked fuel from the traveling distilling-grate B to the combustion-grate C and to prevent clogging 5 by crushing in conjunction with the grate-bars *b* of the grate B any clinker or foreign substances which may not pass over to the grate C—as, for instance, clinkers may adhere to the grate-bars *b*, or slate or other matter may 10 not pass over to the grate C, and in such an event such matter is crushed by the clearing-roll I and drops to the bottom. In my prior patent, No. 692,263, of February 4, 1902, the traveling grate and the combustion-grate were 15 located close together and there was a liability of the two grates being clogged by substances entering between the two, thus stopping the movement of the traveling grate. With the use of the clearing-roll, as described, 20 this cannot happen, and consequently there is no danger of the traveling grate being stopped.

The combustion-grate C is arranged at an incline in a position with its upper end adapted to receive the coked fuel passing over the 25 clearing-roll I and is composed of a series of individual grate-bars overlapping each other with proper provision for the introduction of air from below through the ash-pit.

The dumping-grate D, adapted to remove 30 the accumulating ashes, is hinged at *d* to turn downwardly, and is operated from the exterior by means of the rod K and arms *d'* to remove all ashes passing from the grate C. This grate D may be made solid or in the form 35 of a usual grate.

The last or lowest member of the grate C, I use as an abutment for preventing discharge 40 of fuel from the grate C when the grate D is dumped, the same being mounted to turn and is connected with a rod L, adapted to be operated from the exterior of the furnace for the purpose of turning the same upwardly 45 into the position shown by dotted lines in Fig. 1 before the dumping-grate is turned downwardly, thus retaining the fuel in the grate C. This grate-bar may be made solid or perforated.

The hopper F is provided with a sliding gate *f*, having thereon a series of racks *f'*, 50 adapted to be engaged by gear-wheels *f''*, arranged on the shaft *j*, and said shaft being provided with a ratchet-handle J for raising and lowering said gate for the purpose of regulating the amount of fuel to the traveling grate B.

It is evident that the construction of grates herein described can be applied to all kinds 60 of furnaces adapted for steam-boilers. In Figs. 1, 2, and 3 I have shown a construction particularly adapted for stationary boilers, such as horizontal boilers, return tubular boilers, water-tube boilers, and sectional boilers. In Figs. 7, 8, and 9 I have shown the grate applied to a locomotive-boiler, the

general features being the same, but a frame 65 L' being provided for attaching the inclined grate to the usual bearing-bars located within the fire-box.

In practice I prefer to provide longitudinal side plates S, tapering or inclined downwardly 70 from the walls of the furnace and overlapping the ends of the traveling grate-bars, so as to hold the fuel thereon against lateral displacement.

In the operation of the furnace the following action takes place: First, the carbonaceous matter upon the traveling distilling-grate B is slowly and constantly advanced without admission of air from below and at the ordinary coking temperature, the fire being kindled on this grate as usual; secondly, the coked matter which has received air only from above is passed to a second grate arranged for the ingress of air from below for the purpose of practically complete combustion, while the products of combustion from this second grate mix with the gases produced at a low temperature from the distilling-grate and effect in conjunction the complete combustion of all gases at a high temperature, as 90 well as any fine particles of unconsumed carbon or carbonaceous matter which might be carried off from either grate.

The inclined combustion-grate C may be composed of rocking grate-bars adapted to be 95 turned to the positions shown by dotted lines in Fig. 1 by means of a usual rod M while the furnace is in operation, or it may be turned to the position shown by full lines in Fig. 1 when the furnace is to have the fires banked. 100

What I claim as new is—

1. A combination-grate for furnaces comprising a traveling distilling-grate having individual grate-bars overlapping so as to exclude ingress of air from below, and said grate being of sufficient length to coke the fuel; an inclined combustion-grate adapted to receive the coked matter from the traveling distilling-grate and provided with air-openings between its bars, a dumping-grate adapted to receive 110 ashes from the combustion-grate, and a gate intermediate of the combustion-grate and the dumping-grate for holding the fuel on the combustion-grate when the dumping-grate is actuated, substantially as described. 115

2. A combination-grate for furnaces comprising a traveling distilling-grate having individual grate-bars overlapping so as to exclude ingress of air from below, and said grate being of sufficient length to coke the fuel; an inclined combustion-grate adapted to receive the coked matter from the traveling distilling-grate and provided with air-openings between its bars, and a dumping-grate adapted to receive ashes from the combustion-grate, substantially as described. 120

3. A combination-grate for furnaces comprising a traveling distilling-grate closed sub-

stantially to ingress of air from below the fuel-carrying surface and adapted to carry the fuel from the hopper through sufficient space to coke the fuel, a separate inclined combustion-grate adapted to receive the coked products from the distilling-grate and provided with air-openings, a dumping-grate adapted to receive ashes from the combustion-grate, and a clearing-roll intermediate of the distilling and combustion grates, substantially as described.

4. A combination-grate for furnaces comprising a traveling distilling-grate closed substantially to ingress of air from below the fuel-carrying surface, and adapted to carry the fuel from the hopper through sufficient space to coke the fuel, a separate inclined combustion-grate adapted to receive the coked products from the distilling-grate and provided with air-openings, a dumping-grate adapted to receive ashes from the combustion-grate, and a loosely-mounted corrugated clearing-roll intermediate of the distilling and combustion grates, substantially as described.

5. A combination-grate for furnaces comprising a traveling distilling-grate closed substantially to ingress of air from below the fuel-carrying surface, and adapted to carry the fuel from the hopper through sufficient space to coke the fuel, a separate inclined combustion-grate adapted to receive the coked products from the distilling-grate and provided with air-openings, a dumping-grate adapted to receive ashes from the combustion-grate, and a loosely-mounted clearing-roll transversely divided and intermediate of

the distilling and combustion grates, substantially as described.

6. A combination-grate for furnaces comprising a traveling distilling-grate closed substantially to ingress of air from below the fuel-carrying surface, and adapted to carry the fuel from the hopper through sufficient space to coke the fuel, a separate inclined combustion-grate adapted to receive the coked products from the distilling-grate and provided with air-openings, a dumping-grate adapted to receive ashes from the combustion-grate, and a loosely-mounted tubular clearing-roll intermediate of the distilling and combustion grates, substantially as described.

7. A traveling grate for furnaces comprising a series of grate-bars overlapping each other and adapted to come into contact one with the other for the purpose of closing off ingress of air from below at the combustion-surface, substantially as described.

8. A traveling grate for furnaces comprising a series of grate-bars overlapping each other and adapted to come into contact one with the other for the purpose of closing off ingress of air from below at the combustion-surface, and side guards overlapping the ends of bars of the traveling distilling-grate, substantially as described.

In testimony whereof I have hereunto set my hand in the presence of two subscribing witnesses.

FREDERICK GIRTANNER.
